UNITED STATES PATENT OFFICE.

JOHN W. BOUGHTON, OF PHILADELPHIA, PENNSYLVANIA, ASSIGNOR TO THE BOUGHTON FLYING MACHINE COMPANY, A CORPORATION OF SOUTH DAKOTA.

AIRSHIP.

1,138,724.

Specification of Letters Patent. Patented May 11, 1915.

Application filed May 24, 1913. Serial No. 769,538.

To all whom it may concern:

Be it known that I, JOHN W. BOUGHTON, a citizen of the United States, residing in the city and county of Philadelphia, State of Pennsylvania, have invented a new and useful Airship, of which the following is a specification.

My invention consists in providing an air ship with a pontoon or like device which is adapted to float the same should it drop into water, said device being formed of independent sections either of which will be serviceable should another section, one or more, burst, collapse or be otherwise fractured.

It consists further of a novel construction of a rack for supporting said sectional pontoon.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of an air ship embodying my invention. Fig. 2 represents a longitudinal section thereof. Fig. 3 represents a plan or top view of one of the planes of the ship, on an enlarged scale. Fig. 4 represents a transverse section thereof on line $\alpha-\alpha$ Fig. 3. Figs. 5, 6, 7 and 8 represent sections of different embodiments of said plane. Fig. 9 presents a top or plan view of another embodiment of said plane. Fig. 10 represents a partial side elevation and partial longitudinal section of a pontoon employed, the same being on an enlarged scale. Fig. 11 represents a perspective view of the rack or carrier of said pontoon. Fig. 12 represents a top or plan view of the alighting device employed. Fig. 13 represents a longitudinal section thereof.

Similar numerals of reference indicate corresponding parts in the figures.

Referring to the drawings: 1 designates the frame of the ship, the same being constructed of suitable metal bars or plates which are light and strong in their nature, riveted together or otherwise firmly connected.

2 designates propellers which are mounted on said frame, and receive power in any desired manner.

3 designates a cabin which is supported on and connected with the frame 1 and occupies the center of the same in the longitudinal direction thereof. Within said cabin are suitable guns 4 which are supported on the floor thereof and so mounted as to be capable of being sighted as desired, said guns and the cannoniers or artillerymen being protected in said cabin by the walls thereof, said cabin being adapted also to carry other passengers, ammunition stores, etc.

Surmounted on the frame are planes composed of wings 5 whose forward ends are deflected downwardly and rearwardly forming the elbows 6, under which when the ship is in flight, air may pass, they serving as pockets to assist in creating a vacuum under said wings, it being seen that when the ship is in motion, air impinges on the front of said elbows and the current thereby created is impelled under the latter and so impacts itself forcibly against the rear of the same and consequently against the under face of the wings with cyclonic effects. Simultaneously therewith, a vacuum is created by said wings on the upper faces thereof, and thus the wings act to cause the ascent and flight of the ship with great ascending and sustaining power and swiftness, and the ship may glide with ease while its descent is controllable and may be made gently and with comparative safety. On the side ends of said wings are guards 7 which consist of plates which rise upright therefrom and serve to prevent lateral deflection of air on the backs or upper faces of the wings thus retaining or preserving as it were the vacuums on said faces or backs, and rendering them effective in their actions on said wings.

The elbows 6 and portions of the frame that carries the same are constructed of light metal or other suitable material and the bodies 8 of the wings are formed of light but strong and durable fabric which is passed around said frames and elbows and firmly secured thereto while being braced as desired to increase the strength of the wings, said bodies being closed in front at top and rear, while being opened from below to admit air to the inner faces of the elbows as above stated.

The wings are arranged horizontally in

the frame fore and aft and in tiers, particularly in front so as to produce the best effects of flight of the ship.

Connected with the base of the frame on opposite sides thereof are the pontoons or rafts which are formed of separate or sectional hollow caissons 9 which are placed end to end in the rack 10, the latter being divided in longitudinal directions and held together by bands or straps 11 admitting, however, of access to the caissons 9 when so desired, it being noticed that the caissons contain air gas, etc., to impart buoyancy to the same so that the pontoons or rafts are adapted to float, a feature of importance should the ship drop into water. Should either section of the caisson leak, collapse or be fractured or injured otherwise, the remaining sections will remain intact and so preserve sufficient buoyance or flotation for pontoons. When the ship returns to the earth, it is adapted to run on the land on the rollers or wheels 12 which are mounted on the lower ends of the frame 1 on opposite sides thereof, but the fore wheels have their axes on the radial arms 13, which are pivotally mounted on the adjacent portions of the frame 1. The inner limbs of said arms have springs 14 attached to them, the same being also connected with adjacent portions of the frame 1. Within the arms are blocks 15 preferably of wood, the same projecting in part below said arms forming brake shoes which are adapted to contact with the ground or earth, it being evident that when the ship descends and is about to alight, the fore rollers contact and touch the ground or earth, and as the weight of the ship is imposed on said rollers, the arms 13 yield resiliently and so the wheels strike the ground or earth with ease and so pre-

vent injurious shocks to the ship. Then the shoes 15 engage the ground or earth and act as brakes to slow and stop the motion of the ship thereon. An additional cannon or gun 45 16 is supported on the cabin intermediate of the fore and aft guns 4, it being elevated and placed beneath the cover 17 over the cabin, but the number or style of the cannon or guns I do not limit myself. 50

Having thus described my invention what I claim as new and desire to secure by Letters Patent, is:—

1. In an air ship, a frame, and a buoyant 55 pontoon of separable hollow caissons arranged end to end lengthwise of the ship and supported on said frame.

2. In an air ship, a frame, and a buoyant 60 pontoon of separable hollow sections arranged end to end lengthwise of the ship, combined with a longitudinally divided support in which said sections are removably held.

3. In an airship, a frame, a buoyant 65 pontoon composed of separable hollow caissons arranged end to end lengthwise of the ship, a longitudinally divided support in which said caissons are removably located, and means holding said longitudinally divided support fixedly in position. 70

4. In an airship, a frame, a buoyant 75 pontoon formed of separable hollow members disposed end to end in the direction of the length of the ship, and a rack secured to said frame and divided in longitudinal directions, and having means embracing said hollow members and detachably holding them in the rack.

JOHN W. BOUGHTON.
